IRONING BOARD

Albert Chobanian, 25 Big Oaks Road, Streamwood, Ill.

Filed Aug. 29, 1963, Ser. No. 76,392

Term of patent 14 years

(Cl. D49—1)

FIG. 1 is a perspective view of an ironing board, showing my new design; and

FIG. 2 is a side elevation of the ironing board.

The side not shown is substantially the same as that shown.

I claim:

The ornamental design for an ironing board, as shown and described.
